(57) **CLAIM**

The ornamental design for a flameless candle, as shown and described.

DESCRIPTION

FIG. 1 is a perspective front view of a flameless candle of the present invention;

FIG. 2 is a front side view of the flameless candle;

FIG. 3 is a back side view of the flameless candle;

FIG. 4 is a left side view of the flameless candle;

FIG. 5 is a right side view of the flameless candle;

FIG. 6 is a top side view of the flameless candle; and,

FIG. 7 is a bottom side view of the flameless candle.

The broken lines illustrate portions of the flameless candle that form no part of the claimed design.
